COLLAPSIBLE TUBE HOLDER

Ernest L. Lahtinen, Minneapolis, Minn.

Application April 24, 1943, Serial No. 484,386

6 Claims. (Cl. 248—108)

This invention relates to new and useful improvements in holders for collapsible tubes such as are commonly used for tooth paste, shaving cream, and analogous materials.

Numerous attempts have heretofore been made to develop a device for supporting collapsible tubes of tooth paste and shaving cream, to render said tubes more convenient for daily use, and to eliminate the operation of unscrewing the usual closure cap from the tube and subsequently replacing it thereon. Such a device to be practical, must be so constructed as to be capable of supporting the tube in a conveniently accessible manner with the usual closure cap removed therefrom and with the assurance that when the open tube is supported thereby, its open end or mouth will be sealed to the atmosphere and against all foreign matter which might contaminate the contents of the tube, when the closure cap is not replaced upon the tube neck.

Devices heretofore devised for holding collapsible tubes with their usual closure caps removed therefrom have not been entirely satisfactory; first, because they have not been very sanitary; secondly, because they have not provided a substantially air-tight closure for the open mouth of the tube when the tube is not in use; and thirdly, because in many cases the effort required in their operation was as great as that required for removing and replacing the cap on the tube.

The novel invention herein disclosed, contemplates the provision of a collapsible tube holder which is so constructed that it presents the utmost in sanitation; provides a substantially air-tight closure for the mouth of the tube, when the latter is supported in the holder; and provides maximum utility since less time and effort required on the part of the user to withdraw the tube from the holder and subsequently replacing it therein, than is now required to remove a conventional closure cap from the tube and later replacing the cap on the tube, whereby the use of this novel device will tend to stimulate the daily use of toothpaste.

An important feature of the invention therefore is to provide a holder of the class described having means for frictionally receiving the upper end of a collapsible tube body with the usual closure cap removed therefrom, and whereby the open mouth of the tube is closed to the atmosphere and the contents in the neck of the tube are not likely to become dry and unusable, and also whereby the tube may be conveniently removed from the holder, as when a portion of the contents thereof is to be ejected from the tube, and also

whereby the top end of the tube may be quickly and conveniently inserted into the holder to seal the open top thereof when the tube is not in use.

A further object is to provide a collapsible tube holder having an inwardly turned annular flange defining an opening adapted to receive the upper portion of the tube body in such a manner that said flange will frictionally engage the upper portion of the tube in substantially leak-tight relation, and a second sealing element being provided within the holder adapted to engage the usual upper conical wall of the tube body to further seal the mouth of the tube, and said second sealing element in addition to sealing the tube mouth, also provides a limit stop for the upward movement of the tube, when inserted into the holder, thereby to prevent the upper end of the threaded neck of the tube from engaging the upper wall of the holder and causing some of the contents of the tube to adhere thereto.

A further object is to provide a holder of the class described which readily lends itself to manufacture in quantity production from such materials as plastics, and various other materials, which may readily be molded into the desired shape to provide, in combination, a housing for receiving and enclosing the mouth end of the tube, and a bracket whereby the holder may be conveniently mounted upon a wall in a bathroom where such tubes are commonly used, and whereby the tube may be supported at a convenient location, ready for immediate use.

A further object is to provide a holder for collapsible tubes, comprising a bracket adapted for wall mounting and having a housing supported thereon provided with an open bottom, and a flexible insert being fitted into said housing and provided with an inwardly turned flexible flange defining an opening adapted to receive the discharge end of the tube body, and said insert having a cylindrical flange depending from its upper wall whose lower edge is adapted to engage the upper conical wall of the collapsible tube body, thereby to cooperate with said inwardly turned flange to provide a dual seal for sealing the open mouth of the tube, when the latter is supported in the holder.

A further object is to provide a holder for collapsible tubes, comprising a housing provided with suitable mounting means, and said housing having an annular inwardly turned flange adjacent to its bottom which flange defines an opening of slightly less diameter than the diameter of the tube body, whereby when the end of the tube body is inserted thru said opening, the wall of the

opening is slightly expanded to thereby cause the flange to frictionally engage the tube body in leak-tight relation and in a manner to removably support the tube from said housing, and an annular seat being provided within the housing in vertically spaced relation to said flange adapted to be engaged by the upper conical wall of the tube to provide a limit stop for the tube, when inserted into the housing, and which seat also serves to further seal the open end or mouth of the tube.

Other objects of the invention reside in the provision of a holder for collapsible tubes comprising a housing having an annular seat therein adapted to removably receive and support an annular channel-like member having inwardly directed annular flexible flanges defining openings adapted to receive the body and neck of the tube, respectively, said flanges engaging the tube body with sufficient pressure to seal the mouth of the tube, when the tube is inserted into said housing; in the provision of a device of the class described which may be molded from suitable plastics, and has an annular flexible flange adapted to frictionally engage the tube body to support the tube from said bracket with its open end or mouth enclosed within the housing; in the provision of a tube holder comprising a housing having a flexible cylindrical sealing member mounted therein adapted to engage the upper conical wall of the tube, and a second flexible element of relatively larger diameter having an inwardly directed annular flange defining a restricted opening thru which the end of the tube body may be inserted by slightly deflecting the marginal edge of said flange, whereby the latter will support the tube in the housing in substantially leak-tight relation; and in a device of the class described which is very simple and inexpensive in construction, is very neat and attractive in appearance, and is provided with means for mounting it upon the wall of a bathroom, or some other fixed support suitable for the purpose.

Other objects of the invention will appear from the following description and the accompanying drawing, and will be pointed out in the annexed claims.

In the accompanying drawing there has been disclosed a structure designed to carry out the various objects of the invention, but it is to be understood that the invention is not confined to the exact features shown, as various changes may be made within the scope of the claims which follow.

In the drawing:

Figure 1 is a side view of my improved holder partially in section, showing a collapsible tube suspended therefrom with its open mouth sealed to the atmosphere.

Figure 2 is a sectional view of the flexible insert, removed from the housing;

Figure 3 is a bottom view of Figure 2;

Figure 4 is a view similar to Figure 2, but showing an insert having a relatively smaller bottom opening therein adapted to support a tube of smaller diameter;

Figure 5 is a view showing a holder of slightly different construction wherein the resilient insert is provided with inwardly directed spaced parallel flanges:

Figure 6 is a view similar to Figure 5, but showing the tube removed from the holder;

Figure 7 is a view showing a holder in which two sealing elements are provided within the housing for engaging the end of the tube;

Figure 8 is a view showing the sealing elements of Figure 7 removed from the housing; and

Figure 9 is a view showing another modification wherein the housing, including the gripping and sealing members, may be integrally formed of rubber, or some other material applicable for the purpose, and wherein the housing is detachably secured to the mounting flange.

The invention, as illustrated in Figure 1, is shown comprising a dome-shaped housing 2 having an opening 3 at its bottom defined by an inwardly turned flange 4. The housing 2 is preferably formed with a neck 5 to which is secured 10 two suitable mounting flange 6 provided with apertures 7, whereby the holder may readily be secured to a wall or other fixed support in the position shown in Figure 1.

shown in Figure 1. An important feature of the present invention resides in the means provided within the housing for supporting a collapsible tube 8 from the holder, and whereby the open end or mouth of the tube is completely enclosed within the housing, thereby to prevent exposure of the contents to the atmosphere and contamination thereof by foreign matter. The collapsible tube 8, as best shown in Figure 1, comprises the usual cylindrical body 9, and the conical wall 11 to which a threaded nipple 12 is secured. Before inserting the tube end into the housing, the usual closure cap of the tube, not shown, is removed from the tube.

In a device of the character herein described, sanitation is of paramount importance, and it is therefore highly desirable that the upper-most end 13 of the tube nipple 12 be so supported within the housing that it cannot engage the upper wall of the housing, which might cause some of the contents of the tube to adhere thereto.

To thus support the upper or discharge end of the collapsible tube within the housing, the housing 2 is shown provided with an insert 14 which is preferably made of rubber or some other suitable flexible water-proof material. This insert is shaped to conform substantially to the interior surface of the wall of the housing, whereby it may be fitted into the housing, as shown in Figure 1, and is retained therein by the flange or bead 4 at the bottom of the housing.

The insert 14 is provided at its bottom with a horizontal inwardly turned annular flange 15 defining an opening 16 adapted to receive the body 9 of the tube, as shown in Figure 1. The opening 16, it will be noted by reference to Figures 1 and 2, is relatively smaller in diameter than the diameter of the tube body, whereby when the tube body is inserted thru said opening, the marginal edge of the flange 15 will flex, as shown at 17 in Figure 1, thereby frictionally engaging the body of the tube in such manner as to readily support the upper end of the tube within the housing, and at the same time providing substantially an air-tight seal between the flange 15 and the body of the tube.

To further seal the open end of the collapsible tube and to prevent the end 13 of the nipple from engaging the upper wall portion 18 of the insert, a depending cylindrical flange 19 is shown provided on the upper wall portion 18 of the insert. The flange 19 extends downwardly from the wall portion 18 and preferably has its lower edge beveled, as indicated at 21. The depth of the flange 19 is such that when the end of the tube body is inserted thru the opening 16 in the insert, and the conical wall 11 of the tube engages the beveled edge of the flange 19, the flange 19 will prevent the end 13 of the tube nipple from entering the body of the tube.

gaging the upper wall of the insert, as clearly illustrated in Figure 1. To thus prevent the upper end of the tube from engaging the wall 18, will greatly minimize the danger of portions of the contents of the tube contacting said upper wall and accumulating thereon. The cylindrical flange 19 also cooperates with the horizontal flange to seal the open mouth of the tube.

When the tube is removed from the holder, the interior of the housing may readily be thoroughly cleansed, or, if desired, the insert 14 may be completely removed from the holder to facilitate cleaning and sterilizing, which greatly enhances its usefulness, in that the device may readily and conveniently be maintained in a thoroughly sanitary condition at all times. In the form of the invention as shown in Figure 1, inserts having different size openings 16 therein may be provided, whereby the holder may be used for supporting tubes having different body diameters by simply substituting one insert for another, depending upon the size tube to be supported.

In Figure 4 there is shown an insert 14' having a relatively smaller opening 16' provided at its bottom flange 15', whereby the insert 14' is adapted to support a collapsible tube whose body diameter is relatively smaller than the tube shown in Figure 1. The depending cylindrical flange 19' provided in the insert 14' may also be slightly smaller in diameter to provide a better fit with the conical wall 11 of the tube.

In Figure 5 there is shown a holder comprising a housing 21, which is quite similar to the housing 2 shown in Figure 1, and which, in like manner, is provided with a neck 5 having a flange 6 adapting the holder for wall mounting. The housing 21 is shown provided with an annular cylindrical seat 22 into which is removably fitted an insert 23. The insert 23 is provided with inwardly directed annular flanges 24 and 25, vertically spaced apart, as best shown in Figure 6. The lower flange 24 defines an opening 26 for receiving the upper end portion of the cylindrical tube body 9. The upper flange 25 defines a relatively smaller opening 27 adapted to receive the nipple 12 of the collapsible tube 8, and is adapted to engage the upper end wall 11 of the tube body, as shown.

The opening 26, like the opening 16 in the flange 15, is slightly smaller in diameter than the diameter of the tube body to be supported, whereby the marginal edge of the flange 24 will flex, when engaged by the tube body, as shown in Figure 5. The upper flange 25, as previously stated, is adapted to engage the conical wall 11 of the tube to limit upward movement of the tube into the housing, and also to provide an additional seal for the mouth of the tube, as will be understood. The insert 23 is preferably made of rubber or some other suitable flexible water-proof material which may readily be deformed to permit it to be fitted into the housing or to be removed therefrom.

In Figures 7 and 8 there is shown another form in which the housing 28 is of slightly different form. The housing is preferably provided with a mounting flange 6, similar to the one shown in Figures 1 and 5. The housing 28 has an enlarged annular recess 29 adapted to receive a flexible insert 31, having an inwardly turned horizontal flange 32 whose marginal edge 33 is adapted to frictionally engage the body 9 of a collapsible tube to pendants support the tube from the housing, and to provide substantially a seal.

tight connection between the flange 32 and tube body.

A small recess 34 is shown provided in the upper portion of the housing 28, and below the recess 34 there is provided an annular seat 35 adapted to receive a suitable flexible sealing element 36. The inner lower corner of the sealing element 36 is adapted to engage the conical wall 11 of the tube body, as shown in Figure 7, when a tube is inserted into the housing. The inserts 31 and 36 are made of a suitable flexible waterproof material, preferably rubber, and may readily be removed from the housing 28, as shown in Figure 8.

15 In Figure 9, there is shown a holder comprising a housing 37 which may be molded or otherwise formed of such material as rubber, having a neck 38 shown provided with an opening or bore 39 adapted to receive a supporting stem 41. 20 The supporting stem 41 may be secured to a suitable mounting flange 42, adapted to be secured to a wall or other support. The housing is removably fitted onto the supporting stem 41, whereby it may readily be removed from the 25 mounting flange 42, when desired, to facilitate cleaning and sterilizing or to substitute holders to accommodate tubes of various sizes. The form of housing shown in Figure 9 comprises an annular recess 43 having a central tube-receiving opening in its bottom defined by an annular flexible flange 44. The marginal edge of the flange 44 is adapted to engage the body 9 of a collapsible tube, as shown, thereby to removably support the tube from the housing.

30 35 A relatively smaller recess 45 is formed in the upper portion of the housing for receiving the nipple 12 of the tube. An annular shoulder 46 is provided between the recesses 43 and 45 adapted to engage the conical wall 11 of the tube body, thereby to limit upward movement of the tube and to further seal the open mouth thereof.

40 45 The novel holder herein disclosed, may readily be molded from any of the well known plastics or rubber, and provides a very simple and inexpensive device which is neat and attractive in appearance, and is thoroughly sanitary. When mounted upon a wall in a bath room, the holder provides an ideal support for a collapsible tube of tooth paste, shaving cream, or any other material which may be contained in a collapsible tube, whereby the tube may be readily and conveniently withdrawn from the holder and replaced therein by the user with a minimum of effort and care.

50 55 One of the important features of the invention as hereinbefore stated, resides in the fact that the inwardly turned flange 17 which engages the body 9 of the tube, is continuous around its entire circumference, whereby when the end 60 of the tube body is inserted thru the opening 16 of the flange into the housing, the marginal edge of the flange 17 will grip the body of the tube with sufficient pressure to prevent the tube from accidentally becoming detached from the housing, and at the same time providing an airtight seal between the flange and the tube body.

65 The dual sealing elements provided in each of the various forms of the invention, as herein described, are also important, in that with such an arrangement of dual sealing elements, it is practically impossible for atmospheric air to gain entrance into the upper portion of the housing wherein the open mouth of the tube is supported. This is a highly desirable feature in that it prevents evaporation of the moisture in the con-

tents supported in the neck of the tube, and also prevents contamination of the tooth paste from foreign matter. The construction of the holder is also such as to provide the utmost in sanitation, as will readily be understood by reference to Figure 1.

It will be apparent to those skilled in the art that I have accomplished at least the principal objects of my invention, and it will also be apparent to those skilled in the art that the embodiments herein described may be variously changed and modified without departing from the spirit of the invention, and that the invention is capable of uses and has advantages not herein specifically described; hence it will be appreciated that the herein disclosed embodiments are illustrative only, and that my invention is not limited thereto.

I claim as my invention:

1. A holder for supporting a collapsible tube with its closure cap removed from the mouth of the tube, said holder comprising a housing provided with an upper wall and an elastic bottom wall having a central opening therein adapted to receive one end of the tube, the diameter of said opening being relatively less than the diameter of the tube body, whereby the marginal edge of said elastic wall will frictionally engage the tube body in substantially leak-tight relation and pendants support the tube from the holder with the open mouth of the tube enclosed within the housing, and means within the housing above said elastic wall adapted to engage the upper portion of the tube to provide an auxiliary closure for the open end or mouth of the tube when supported in said housing.

2. A holder for supporting a collapsible tube with its closure cap removed from the mouth of the tube, said holder comprising a closed housing provided at its bottom with an elastic wall having a central opening therein whose diameter is relatively less than the diameter of the body of the tube to be supported by said holder, whereby when one end of the tube is inserted thru said opening, said elastic wall will frictionally engage the tube body and pendants support it from said holder with the open mouth of the tube enclosed within the housing, and means within the housing above said flange adapted to be engaged by the upper conical wall of the tube, thereby to limit upward movement of the tube in said housing.

3. A holder for supporting a collapsible tube with its closure cap removed from the mouth of the tube, said holder comprising a housing provided at its bottom with an inwardly turned annular elastic flange adapted to frictionally engage the tube body in substantially leak-tight relation and pendants support the tube from said holder, and an annular seat spaced upwardly from said flange adapted to be engaged by the

upper conical wall of the tube body to thereby cooperate with said flange to further seal the open mouth of the tube.

4. A holder for supporting a collapsible tube with its closure cap removed from the mouth of the tube, said holder comprising a housing having a dome-shaped upper wall and provided at its bottom with an annular continuous flange capable of yielding under pressure, the marginal edge of said flange defining an opening adapted to receive the discharge end of the tube body, said opening being relatively smaller in diameter than the diameter of the tube body whereby when the discharge end of the tube body is inserted into the housing thru said opening, the marginal edge of said flange will yield or stretch to permit passage of the tube body therethru, and will frictionally engage and support the tube from the holder with the upper end of the tube enclosed within the housing, said flange engaging the tube body in substantially leak-tight relation, and an annular seat in said housing spaced upwardly from said flange and adapted to be engaged by the usual conical wall at the discharge end of the tube, thereby to further seal the open mouth of the tube, said seat also limiting movement of the tube into the housing to prevent its open end from engaging the upper wall of the housing.

5. In a device of the class described, a dome-shaped housing having an imperforate top wall and an open bottom and provided with means for supporting it on a wall or fixed support, a member removably fitted into said housing and having an inwardly turned continuous elastic flange defining an opening adapted to receive and frictionally support a collapsible tube body from the housing, a relatively smaller elastic flange disposed within the housing and arranged to be engaged by the upper conical wall of the tube body, thereby to seal the open top of the tube to the atmosphere.

6. In a device of the class described, a housing having an open bottom, an elastic member removably fitted into said housing and having an inwardly turned annular flange defining a central opening in the bottom of the housing adapted to receive the body of a collapsible tube, said opening being relatively smaller in diameter than the tube body whereby its wall is expanded by the insertion of the tube body therethrough, whereby said expanded wall will frictionally grip the tube body and support it from the housing, a cylindrical flange depending from the upper wall of said member in position to engage the upper conical wall of a tube inserted into said central opening, said cylindrical flange limiting upward movement of the tube body in the housing and cooperating with said inwardly turned flange to provide a dual seal for the upper open end of the tube.

ERNEST L. LAHTINEN.
